UNITED STATES PATENT OFFICE.

HARRY A. SCHNELBACH, OF CRAFTON, PENNSYLVANIA, ASSIGNOR TO JEFFERSON GLASS COMPANY, OF FOLLANSBEE, WEST VIRGINIA.

DESIGN FOR A LAMP-SHADE.

40,894.

Specification for Design. Patented Sept. 20, 1910.

Application filed July 21, 1910. Serial No. 573,155. Term of patent 7 years.

To all whom it may concern:

Be it known that I, HARRY A. SCHNELBACH, a citizen of the United States, residing at Crafton, in the county of Allegheny and State of Pennsylvania, have invented a new, original, and ornamental Design for Lamp-Shades, of which the following is a specification, reference being had to the accompanying drawing, forming part thereof.

top view, of a lamp shade, showing my new design.

I claim:

The ornamental design for a lamp shade, as shown.

HARRY A. SCHNELBACH.
